CLAIM

The ornamental design for a combined heat sink and radiator for electronic equipment, as shown and described.

DESCRIPTION

FIG. 1 is a top, right and front perspective view of a combined heat sink and radiator for electronic equipment showing my new design;

FIG. 2 is a right side elevational view thereof;

FIG. 3 is a left side elevational view thereof;

FIG. 4 is a bottom plan view thereof;

FIG. 5 is a front elevational view thereof; and,

FIG. 6 is a rear elevational view thereof.

FIG. 1

FIG. 2

FIG. 3

FIG. 4

FIG. 5

FIG. 6
